UNITED STATES PATENT OFFICE.

ISAAC N. TOPLIFF, OF CLEVELAND, OHIO.

CARRIAGE-BOW.

SPECIFICATION forming part of Letters Patent No. 446,938, dated February 24, 1891.

Application filed October 18, 1889. Serial No. 327,447. (No model.)

To all whom it may concern:

Be it known that I, ISAAC N. TOPLIFF, a citizen of the United States, residing at Cleveland, in the county of Cuyahoga and State of Ohio, have invented certain new and useful Improvements in Carriage-Bows, of which the following is a specification, reference being had therein to the accompanying drawings.

This invention has for its object to simplify 10 the construction of carriage-bow slat-irons so as to form a strong and substantial support for the bows.

In the drawings, Figure 1 is a side elevation showing the lower portions of a set of 15 carriage-bows connected to the socket. Fig. 2 is a central vertical section taken through the main bow and slat-iron, and Fig. 3 is a perspective view of the slat-iron, showing the socket therein.

20 A is the main bow of a carriage, and A' A² the bows located at each side of the same. The shank *a* of the main bow is threaded externally, as shown in Fig. 2, for the purpose hereinafter explained.

25 B is the slat-iron, which is formed with an eye at its lower end, as usual. The upper end of said slat-iron is provided with an internally-screw-threaded socket *b*, into which the threaded shank *a* of the main bow A is screwed.

30 The slat-iron is provided with lateral arms *b'*,

which are preferably formed integral with it. The slat-iron and extensions have a plain surface at one side, and to the said side the bows A' A² are pivoted.

As constructed, the slat-iron forms a very 35 strong and rigid support for the main bow, while it permits the said bow to be so constructed that the leather covering may be sewed and drawn on before the bow is secured in its socket, thus dispensing with hand 40 labor, which has been necessary in covering the bows as heretofore constructed and attached.

Having now described my invention, what I claim is—

45 The combination, with the slat-iron of a carriage having a central screw-threaded socket and lateral extensions, the faces of the extensions and the central portion of the socket at one side being in a common plane, 50 of the main bow screw-threaded at its end and secured in said socket, and the side bows pivoted to the faces of the extension at the side in the same plane with the side of the socket, substantially as described.

ISAAC N. TOPLIFF.
